UNITED STATES PATENT OFFICE.

ARTHUR S. BEMIS, OF CLEVELAND, OHIO, ASSIGNOR, BY MESNE ASSIGNMENTS, TO NATIONAL CARBON COMPANY, INC., A CORPORATION OF NEW YORK.

PROCESS OF MAKING RESISTER PLATES.

1,282,029.

Specification of Letters Patent.

Patented Oct. 22, 1918.

Application filed April 22, 1914. Serial No. 833,636.

To all whom it may concern:

Be it known that I, ARTHUR S. BEMIS, a citizen of the United States, residing at Cleveland, in the county of Cuyahoga and State of Ohio, have invented a certain new and useful Improvement in Processes of Making Resister-Plates, of which the following is a full, clear, and exact description.

This invention concerns resistors adapted to withstand high temperatures without rapid disintegration by oxidation. Resistors of this kind are very largely required in electric furnaces of the resistance type and are very useful in many other forms of electrical apparatus. However, the principal use of the resistor described herein is in electric furnaces for melting metals and alloys, particularly brasses. For this purpose, carbon plates have been most widely used on account of their low conductivity and ability to withstand high temperatures without melting or softening. Carbon plates are not satisfactory, however, when heated with free access of air at or above a red heat. When thus heated, they must be used in a reducing or indifferent atmosphere. To obtain these conditions in ordinary furnace operation is usually inconvenient, difficult and expensive. In fact it is almost impossible in a commercial furnace to entirely exclude the oxygen of the air, and it therefore unites with the intensely heated carbon plates and causes them to be more or less rapidly consumed at the exposed surfaces.

The resistor rings or plates, which are generally arranged in piles, are acted upon at the exposed edges and the combustion or disintegration of the carbon proceeds inward toward the center. The contact surfaces between the plates are but very little acted upon because they fit snugly and the air does not penetrate between the plates. It has therefore been proposed to coat the edges with some material which is not oxidized to any extent under the action of the air when highly heated. A number of non-oxidizable materials have been proposed for similar purposes, but the most satisfactory for use with carbon resistors is probably carborundum, and the socalled carborundum "fire sand" which consists of carborundum and compounds between silicon, carbon and oxygen.

My invention accordingly relates to an ad-

vantageous method of applying a coating of 55 protective material to a carbon resistor, but while I describe the method with reference to carborundum "fire sand" it can be used to apply a protecting sheath of any other material such as titanium carbide, aluminum nitride, etc. For convenience of expression, the "fire sand" is hereafter referred to as carborundum.

In the drawings, which illustrate several modifications of apparatus suitable for carrying out the method—

Fig. 1 shows a mold with partitions therein for making a single resistor.

Fig. 2 shows a mold with partitions therein for making a plurality of resistors 70 simultaneously.

Fig. 3 is a plate for changing the depth of the mold.

Fig. 4 is a member for closing certain spaces formed by the partitions.

Fig. 5 shows the member of Fig. 4 placed in position in the mold.

Fig. 6 is an arrangement which may be substituted for the closing member of Fig. 4.

Fig. 7 is a modification of the device of 80 Fig. 4.

Fig. 8 illustrates a form of plunger to be used with the mold of Fig. 1.

Fig. 9 shows the mold and plunger combined with the compression means.

Fig. 10 is a finished resistor plate.

Fig. 11 is another filling device.

Protective coatings and edges have previously been applied by dipping the portion to be coated or by forming the resistor and the 90 coating separately. My invention, however, relates to a method which is applicable for use with the usual apparatus for molding carbon resistance plates and according to this invention, the protective coating or 95 sheath and the resistor are molded simultaneously.

In Fig. 1, I have shown a single mold for carrying out the process. This consists of a mold frame 1 having a cavity of the 100 desired shape and size. In order to properly separate the mix for the resistor portion of the plate from the mix for the protecting edge, a spacer frame 2 of thin metal is placed in the mold as shown. The carbon 105 or other desired mix is then placed in the cavity 3 in the center and the carborundum or other mix is put in the peripheral space

4 outside of the spacer. After the mixes are carefully leveled up the spacer 2 is removed. A plunger that just fits inside the mold frame 1 is then forced into it against 5 the mixes and the same are compressed to form a plate as shown in Fig. 10. I find that the pressure forces the two mixes together so that they cling firmly together and after the plates are baked, the protecting edge 25 and inside resister portions 24 are united together as if the entire plate were made of one mix. When a plate made in this way is put in use, it is found that the protecting edge does not crack off and 10 the resister will last for an extended period even when heated as high as 1800° centigrade. The binder in the carborundum mix and that in the carbon mix, when the plate is baked, binds together the entire mass 15 in a very effectual manner.

The process described above can be carried out by apparatus that will enable a plurality of plates to be molded at the same time. In Fig. 2, such a mold is shown in which 25 three plates can be molded simultaneously. It is, of course, understood that any number greater than this could likewise be simultaneously molded.

Referring to Fig. 2 the mold body 1 consists of a block of metal having a cavity cut in its face of a depth suitable to contain enough material to form a plate of the desired thickness when compressed. The depth is made sufficient to be adapted to the thickness desired resister plate or block and different thickness may be obtained by inserting plates 3' (Fig. 3) of any desired thickness in the bottom of the mold. In the opening 3, a grid or separating frame of sheet metal 35 is inserted. This frame consists of an outer band 6 uniformly spaced from and centered in the mold by means of the projecting lugs 5 to form an outer peripheral space 4^a, 4^b, 4^c and 4^d. The distance between the mold and 40 frame will depend upon the thickness of the protecting edge to be applied to the resister and this may be varied by using different size frames. If only one resister is to be made, as already described, no partitions are placed within the band 6, but if 45 a plurality of plates are to be manufactured simultaneously, say three, then four intermediate parallel strips 7 are fitted therein. As shown in Fig. 1 these strips form five 50 compartments, three of which, 8, 9 and 10 represent the spaces for the resistance material. The compartments 11 and 12, between the compartments 8 and 9, and 9 and 10 respectively, provide the space for 55 the protective edges of the plates, and are therefore, approximately twice the width of the channel 4 because they form the protective edge for two adjacent plates. When 60 the molding piston compresses the mix in 65 the mold two knives will at the same time

cut or score these double edges 11 and 12 so the plates can be separated as is described later.

It is a tedious task to fill the various compartments between the spacer and the mold and to facilitate this I use the device shown in Fig. 4. This device consists of three sheet metal or wooden blocks 13 held together by a member 14 and spaced apart to fit into the compartments 8, 9 and 10 70 to the level of the top of the mold as shown in Fig. 5 so that excess material may be scraped off in filling it. After the carborundum spaces are filled, device 13 is removed, and the carbon spaces are then 80 filled with the mix and the same can be scraped level without substantially disturbing the filled carborundum spaces as the latter are relatively narrow. However if desired, the device shown in Fig. 11 can 85 be used to cover the carborundum spaces while filling and levelling off the carbon spaces 8, 9 and 10. This device is made of thin sheet metal or other suitable material, and when it is fitted in between the pins 1', 90 the turned down ends 16, 16' abut against the sides of the mold body. In this position the slots 23 line with the carbon compartments 8, 9 and 10 while the carborundum compartments are covered up. The carbon 95 mix can now be filled and scraped off level without affecting the carborundum compartments.

Fig. 8 shows a plunger 26 having a V shaped separating member 27. The plunger 10 is operated by the hydraulic press 28 (Fig. 9) to compress the mixes in the mold 1. The plate thus formed is scored or grooved simultaneously by means of the separators 27 so that it may be readily broken at proper 10 places to form three resister plates.

Instead of using the blocks 13 for closing certain openings, the sheet iron plate shown in Fig. 7 may be used. This plate has various openings in its surface that may 11 be lined up with the compartments of the mold body. The distance between the turned down flanges 16' and 17 however, is greater than the width of the mold so that the plate can be slid either to the right or to the 11 left of the mold shown in Fig. 2 with either the flange 16' or the flange 17 abutting against the corresponding end of the mold body. If the outside slots 19, 21 and 22 opened into each other at their adjacent 11 ends, it would not be necessary to slide the plate back and forth in filling the mold, but this is impossible as the central part of the plate would then not be connected to the outside part. It is, therefore, necessary 11 to leave a thin portion between the end of the slots referred to.

In using this plate to fill the carborundum compartments, it is fitted in between the pins 1' of the mold body in Fig. 2 and slid 12

to the right until the flange 16' abuts against the left hand wall of the mold body 1. The carborundum mix is then placed on top of the plate to fill the compartments under the 5 slots 19, 20 and 22. The surplus mix is then scraped off with a straight edge or similar tool. After this operation the compartment 4^a is completely filled and leveled off, while the compartments 4^c, 11, 12 and 4^a are filled 10 and leveled with the exception of that portion of each beneath the webs 19^a, 19^b, 19^c and 19^d respectively. The plate is then moved to the left of the mold body as shown in Fig. 2 until the flange 17 abuts against 15 the right hand end of it. By placing the carborundum mix on the plate and scraping it off level, the compartment 4^b under the slot 21 and the unfilled portions of the compartments 4^c, 11, 12 and 4^a, formerly under 20 the webs 19^a, 19^b, 19^c and 19^d are filled and leveled off. The carborundum compartments are now entirely filled and leveled.

The carbon compartments can then be filled as previously described.

25 It will, of course, be understood that it is immaterial whether the carborundum compartments are filled before filling the carbon compartments as the reverse process may be used. It is likewise immaterial in 30 using the plate shown in Fig. 7 whether it is first slid to the right until flange 16' abuts against the mold body or to the left until the flange 17 abuts against it, as it of course can be used either way.

35 It may be convenient to have the carbon and carborundum covers joined together in one plate and this is shown in Fig. 6. A handle 18 being there shown to manipulate the plate conveniently. By using the 40 proper end of this plate, either the carbon compartments or the carborundum compartments can be filled in the same manner as previously described.

The mix used for the resister portion of 45 the plate may consist of appropriate pulverulent material, and the carborundum or other protecting mix will be used in a pulverulent condition, either with or without a binder, depending on whether the same is 50 necessary. The heavy pressure used to compress the two mixes causes them to be intimately united, and when they are baked a strong and permanent joint is established between the two materials. The line of 55 union between the two is serrated or roughened slightly by the materials flowing slightly into each other when they are compressed which firmly secures them together. By this method the cracking off

of the carborundum, which is the great disadvantage of other methods is minimized.

Although a plate made in accordance with the process just described is much superior to plates made by any process with which I am familiar, continuous use causes 65 a slight disintegration of the outer surface of the carborundum. This, I think, is due to the slow disintegration of the binder which secures the carborundum particles together. I find, however, that if the plates 70 which are baked to a very high temperature, preferably under pressure in such a furnace as is described in the patent of John W. Brown, No. 1,198,616, granted Sept. 19, 1916, this slow disintegration of the carbon 75 sheath is almost entirely eliminated. I am not sure of the reason for this, but I think it is caused by the reaction between the carborundum fire sand and its carbon binder to form a chemical compound, probably carborundum, which is stable at fairly high 80 temperatures in the presence of oxygen.

Although I have described my invention in reference to rectangular plates, it will be evident that it is clearly adaptable to other 85 forms such as segments and sectors of circles, sections of rings, and any other described form.

Having described my invention, what I claim is:

1. The process of making a resister body which consists in filling a protecting material and a resistance material into temporarily separated compartments of a compartment mold, leveling all the material 95 even with the top of the mold, removing the temporary separating means, applying pressure to compact the materials, removing the compacted resisters from the mold and baking to a temperature sufficient to cause the 100 materials to set together.

2. The process of making a resister body which consists in closing certain temporarily separated compartments of a compartment mold, filling the open compartments 105 with a protecting material, leveling off the protecting material even with the top of the mold, removing the closing means and filling the remaining compartments with resistance material, removing the separating 110 means from the mold and applying pressure to compact and unite the materials.

In testimony whereof, I hereunto affix my signature.

ARTHUR S. BEMIS.
